UNITED STATES PATENT OFFICE.

RICHMOND W. WHEELER, OF BUSHNELL, ILLINOIS.

IMPROVEMENT IN CYLINDERS FOR LINING WOODEN PUMPS.

Specification forming part of Letters Patent No. 140,802, dated July 15, 1873; application filed April 26, 1873.

To all whom it may concern:

Be it known that I, RICHMOND W. WHEELER, of Bushnell, in the county of McDonough and State of Illinois, have invented a new and useful Improvement in Cylinders for Lining Wooden Pumps; and I do hereby declare that the following is a full, clear, and exact description of the same, reference being had to the accompanying drawing and to the letters of reference marked thereon making a part of this specification, in which—

Figure 1 is a perspective view of the cylinder. Fig. 2. is a longitudinal section, showing the cylinder inserted in the wooden pump.

My invention relates to that class of cylinders for lining wooden pumps—that is, made of cast-iron and lined on the inside with porcelain. My invention consists in a more substantial means of securing the cylinder rigidly to the pump-stock.

This I do by having cast on the cylinder a wedge-shaped ring, shown at *a*, Figs. 1 and 2, the cylinder being driven into the pump-stock until the ring *a* is some two or three inches beyond the end of the pump-stock, as shown in Fig. 2, at *a*; then an iron band, shown at *c*, is driven over the end of the wooden stock, which shrinks the wood down over the edge of the ring *a*, shown in Fig. 2, and keeps it firm and secure to its place.

Having thus described my invention, what I claim as new, and desire to secure by Letters Patent, is—

The cylinder *d*, as shown, with a wedge-shaped ring, *a*, as and for the purpose set forth.

RICHMOND W. WHEELER.
